DESIGN FOR BACKS OF PLAYING-CARDS.

Design No. 10,238, dated September 11, 1877

UNITED STATES PATENT OFFICE.

ALFRED J. MANNING, OF NEW YORK, N. Y., ASSIGNOR TO ANDREW DOUGHERTY, OF SAME PLACE.

DESIGN FOR BACKS OF PLAYING-CARDS.

Specification forming part of Design No. **10,238**, dated September 11, 1877; application filed August 4, 1877.
[Term of Patent 7 years.]

To all whom it may concern:

Be it known that I, ALFRED J. MANNING, of the city, county, and State of New York, have invented and produced a new Design for the Backs of Playing-Cards, of which the following is the specification:

A molded border, B, incloses an oblong ornamental panel, A, formed by a molded border, a, as shown. The corner-pieces C are ornamented by vines and leaves, as shown. In the center of the large panel A is an ornamental cross, b, arranged within a smaller panel, D, surrounded by an ornamental border, e, as shown. The space between the borders a c is occupied by foliated ornaments s, as shown.

I claim—

1. The design for the back of a playing-card, consisting of the panel A, its border B,

and corners C, ornamented by vines and leaves, substantially as shown and described.

2. The design for the back of a playing-card, consisting of the panel D, substantially as shown and described.

3. The design for the back of a playing-card, consisting of the ornamental cross b, substantially as shown and described.

4. The design for the back of a playing-card, consisting of the panel A, having the border inclosing the ornamental figures, substantially as shown and described.

In testimony whereof I have signed my name to this specification in the presence of two subscribing witnesses.

ALFRED J. MANNING.
